UNITED STATES PATENT OFFICE.

WILLIAM R. BLAIR, OF ST. LOUIS, MISSOURI, ASSIGNOR TO LANDIS MACHINE COMPANY,
OF ST. LOUIS, MISSOURI, A CORPORATION OF MISSOURI.

BOBBIN-RETAINING MECHANISM.

1,152,140.

Specification of Letters Patent. Patented Aug. 31, 1915.

Application filed February 1, 1915. Serial No. 5,531.

To all whom it may concern:

Be it known that I, WILLIAM R. BLAIR, a citizen of the United States, residing at the city of St. Louis, State of Missouri, have invented a certain new and useful Improvement 5 in Bobbin-Retaining Mechanism, of which the following is a full, clear and exact description, such as will enable others skilled in the art to which it appertains to make 10 and use the same, reference being had to the accompanying drawings, forming part of this specification.

My invention relates to sewing machines, and specifically to the form of sewing machine illustrated and described in U. S. Letters Patent No. 743,870 to French and Meyer.

The feature to which my invention is particularly directed is the arrangement for 20 retaining the bobbin-case in the shuttle, and contemplates the provision of a vertically swinging bobbin retaining arm which is adapted to engage the tail of the bobbin-case to retain the case in proper position 25 during the movements of the shuttle. I arrange this arm so that it may be withdrawn entirely from in front of the bobbin-case to a position where it will be completely out of the way of the operator in removing and re- 30 placing the bobbin-case for the purpose of applying filled bobbins. The retaining arm is provided with convenient manipulating means, and means adapted to retain it in its operative and inoperative positions.

35 The principal object of my invention, therefore, is to provide a removable bobbin-case retaining means which is adapted to hold the bobbin-case in proper position, which is easily operable, and which may be 40 withdrawn entirely from in front of the bobbin-case and shuttle to a position where it is completely out of the way of the operator.

Other objects will be hereinafter pointed 45 out or obvious by reference to the accompanying drawings, in which—

Figure 1 is a front view partially in section of a detail of a machine showing the shuttle and bobbin and my improved holding device. Fig. 2 is a top view partly in 50 section showing the same elements.

Referring more specifically to the drawings, in which like reference characters are applied to like parts throughout, it will be 55 understood that 1 represents the shuttle cas-

ing in which is revolvably mounted the shuttle 2. The bobbin-case 4 is mounted in the shuttle in the usual fashion, and has the customary laterally projecting tail 5. The shuttle is actuated in the customary fashion 60 by a suitable driving cam which swings the segment arm 6, the latter coöperating with the pinion 7 which is mounted on the shaft 8 by which movement is transmitted to the 65 shuttle.

On a horizontal pivot pin 9 at one side of the shuttle case is pivoted the bobbin-case retaining member 10. The retaining member is in the form of a bell crank lever having at the extremity of one of its arms 70 the retaining head 11, and at the extremity of its other arm the operating handle 12. At one side of the retaining member is fixed the locking segment 14, and in coöperative relationship thereto there is formed on the 75 retaining member an offset seat portion 15 in which is a locking pin 16. The inner extremity of the locking pin is shaped to co-operate with suitable notches 17 in the segment 14. The locking pin is actuated by an 80 ordinary hand pawl 18 which is pivoted on the handle portion 12 and urged therefrom by a spring 19. The hand pawl has a nose portion operated through a slot in the side of the seat portion 15 and seated in a notch 85 21 in the locking pin. By virtue of this arrangement, the pressure of spring 19 tends to urge the locking pin toward the segment 14, and retain the inner extremity thereof in mesh with either of the notches 17 when 90 properly positioned. Compression of the hand pawl 18 withdraws the locking pin from either of notches 17 in which it may be seated.

In operation, the bobbin case being properly positioned in the shuttle, the retaining member 10 is swung into position so that the head 11 engages the tail 5 of the bobbin case. The head 11 is formed so as to allow a limited movement of the bobbin tail 5 100 therein, but operates to maintain the tail of the bobbin case in approximately the same position during movement of the shuttle. When the retaining member is in this position, the locking pin 16 is in engagement 105 with the upper slot 17, retaining the member 10 in proper position.

When it is desired, for any purpose, to remove the bobbin case, the operator compresses the hand pawl 18, thus withdrawing 110

the locking pin 16, and swings the member 10 on its pivot 9, thus raising head 11 vertically away from the bobbin case to the position illustrated by the dotted lines A in Fig. 5 1. In this position, the locking pin 16 engages the lower notch 17, holding the device in position where it is entirely out of the way of the operator, giving him immediate and full access to the shuttle for the removal of the bobbin case or other operation.

I am aware that minor changes and modifications may be made in the device without departing from the true spirit and scope of the invention indicated in the appended 10 claims.

What I claim is:

1. In a machine of the class described, a member adapted to engage the bobbin case to hold it in operative position, said member being mounted to one side of the shuttle raceway and movable on an axis parallel to the axis of the shuttle for displacement vertically from in front of the shuttle case,

and manually manipulative locking means for retaining said member in operative and 25 inoperative positions.

2. In a machine of the class described, a bell crank retaining member mounted to one side of the shuttle raceway, said retaining member having one of its arms provided 30 with a portion movable in a plane parallel to the face of the bobbin case and adapted to engage the bobbin case to hold it in operative position, and the other of its arms provided with manually manipulative means 35 whereby said member may be swung into operative and non-operative positions and secured in such positions.

In testimony whereof I hereunto affix my signature in the presence of two witnesses, 40 this 29th day of January, 1915.

WILLIAM R. BLAIR.
